P.A.

(57) **CLAIM**

I claim the ornamental design for a braided cable sleeve, as shown and described.

DESCRIPTION

FIG. 1 is a front perspective view of my new design for a braided cable sleeve; and,

FIG. 2 is a rear perspective view thereof.

In the drawings, the broken lines are for the purpose of illustrating environment only and form no part of the claimed design.

1 Claim, 2 Drawing Sheets
